UNITED STATES PATENT OFFICE.

WILLIS S. JONES, OF OAK PARK, ILLINOIS.

DESIGN FOR A RAILWAY-TIE PLATE.

SPECIFICATION forming part of Design No. 34,018, dated January 29, 1901.

Application filed January 3, 1901. Serial No. 42,021. Term of patent 14 years.

To all whom it may concern:

Be it known that I, WILLIS S. JONES, a citizen of the United States, residing at Oak Park, in the county of Cook and State of Illinois, 5 have invented and produced a new and original Design for Railway-Tie Plates; and I do hereby declare the following to be a full, clear, and exact description of the same, reference being had to the accompanying drawings, o forming a part thereof.

This invention relates to new and original design for railway-tie plates, and it is embodied in the original shape and configuration shown in the accompanying drawings.

5 In the drawings, Figure 1 is a perspective view of the plate, and Fig. 2 is an end view.

A designates the plate proper, which has parallel longitudinal depressions therein, the walls of which are curved and meet at substantially right angles. At the edges of the plate are downturned flanges B, slightly ta-

pered, the connection between the flanges and the plate being curved, as shown.

Directly below the channels or depressions in the plate are formed tapered flanges C, 25 which extend longitudinally the length of the plate.

The essential feature of the invention is the plate having the depressions or edge flanges and intermediate flanges, as shown. 30

Having thus described the invention, what is claimed as new, and desired to be secured by Letters Patent, is—

The design for a railway-tie plate, substantially as shown and described. 35

In testimony whereof I affix my signature in presence of two witnesses.

WILLIS S. JONES.
